(57) **CLAIM**

I claim the ornamental design for a coupler member for a latch mechanism used in doors, hatches, and gates, as shown.

DESCRIPTION

FIG. 1 is a top perspective view of a coupler member for a latch mechanism used in doors, hatches, and gates showing my new design;

FIG. 2 is a rear side elevational view thereof;

FIG. 3 is a top plan view thereof, the bottom plan view being identical;

FIG. 4 is a right side elevational view thereof, the left side elevational view being a mirror image; and,

FIG. 5 is a front side elevational view thereof.

The broken line drawing of the apertures in FIGS. 1-5 is for illustrative purposes only and forms no part of the claimed design.
